Attorney.

UNITED STATES PATENT OFFICE.

GEORGE BODEN, OF WATERBURY, CONNECTICUT, ASSIGNOR TO OAKVILLE COMPANY, OF WATERBURY, CONNECTICUT, A CORPORATION OF CONNECTICUT.

EMBROIDERY-RING.

1,318,721.

Specification of Letters Patent. Patented Oct. 14, 1919.

Application filed December 30, 1915. Serial No. 69,890.

To all whom it may concern:

Be it known that I, GEORGE BODEN, of Waterbury, in the county of New Haven and State of Connecticut, have invented certain 5 new and useful Improvements in Embroidery-Rings; and I do hereby declare the following specification, taken in connection with the accompanying drawings, forming a part of the same, to be a full, clear, and 10 exact description thereof.

In embroidery rings as heretofore constructed, it has been customary to employ an endless inner ring and a split outer ring which was provided with means upon the 15 exterior thereof for contracting the outer ring upon the inner ring. This construction has been found objectionable by reason of the fact that the thread or other material used in the embroidering operation would often catch upon the means for contracting the outer ring and become broken or entangled thereby. This contracting means upon the exterior of the outer ring was also unsightly and produced a projection often 20 times having a sharp edge or edges, which was more or less annoying when engaged by the hand of the operator.

It is the principal object of the present invention to obviate these objectionable members and produce a set of embroidery rings 30 in which the outer ring is endless and the inner ring is split and provided with means for expanding the inner ring against the interior of the outer endless ring.

35 A further object consists in providing the expanding means with means for operating the same.

To these ends the invention consists in the novel construction, combination and arrangement of parts hereinafter described, 40 and more particularly set forth in the claims.

In describing the invention in detail reference will be made to the accompanying drawings in which—

45 Figure 1 is a top plan view of a portion of my improved embroidery rings, showing the inner split ring expanded against the inner surface of the outer endless ring.

Fig. 2 is a plan view of a portion of the 50 inner surface of the embroidery rings.

Fig. 3 is a top edge view showing the expanding means in open position and the inner split ring in contracted position.

55 Figs. 4, 5, 6 and 7 are views showing modified forms of the expanding means.

Referring to the drawings, 1 represents the outer endless ring and 2 represents the inner split ring, both of which may be made of any suitable material. Secured upon the inner surface of the split ring 2 adjacent 60 one of the free ends thereof is a hinge-member 3, and secured adjacent the other free end is a corresponding hinge-member 4.

Hinged to and extending between the hinge-members 3 and 4 is a toggle-joint 65 comprising an elongated flat member 5, and a member 6 formed of spring wire and provided upon the upper side with a downwardly extending loop 7, and upon the under side with a corresponding downwardly extending loop 8, as shown in Fig. 2.

In the operation of the device, the material to be operated upon is placed over the inner split ring when the expanding means is in open position, as shown in Fig. 3, and said split ring is inserted within the outer endless ring. The expanding means is then moved to closed position, as shown in Fig. 1, so that the material will be tightly gripped between the inner and outer rings. By reason of 80 the loops 7 and 8 in the wire-member 6 of the toggle-joint, a spring action will be set up in said member to provide for different thicknesses of material, and to securely lock the toggle-joint in closed position.

It will also be seen that the loop 8, extending as it does below the loop of the inner split ring, serves as means to be engaged by the fingers of the operator to operate the 85 toggle-joint or expanding means.

Figs. 4 and 5 show a modified construction, in which both members of the toggle-joint are made of flat sheet metal, the member 5 being provided with a spring loop 9 which extends into the space between the free ends of the split-ring when said ring is expanded into engagement with the outer ring, as shown in Fig. 4. The member 6' is provided with a downwardly extending projection 10, which serves as means for operating the toggle-joint.

Figs. 6 and 7 show another modified construction of the toggle-joint, in which the member 5'' is provided with both the spring-loop 9'' and the operating means 10'', the 95 second member of the toggle-joint being in the form of a plain flat strip 6''.

With the construction above described, it will be seen that the means for expanding the inner split ring is all upon the interior 110

of the ring and beneath the fabric which is being operated upon, and that the outer endless ring presents a smooth surface throughout its entire circumference, and that 5 there is no projection thereon with which the thread of the operator is liable to become engaged. It will also be seen that a very simple and strong means is provided for expanding the inner split ring against the 10 outer endless ring.

What I claim as my invention and desire to secure by Letters Patent is:

1. In an article of the character described, the combination with an outer endless ring 15 of an inner resilient split-ring provided upon its inner surface with a two-member toggle-joint connecting the ends thereof, one portion of said toggle-joint being resilient and provided with a lateral projection for 20 operating the same.

2. In an article of the character described, the combination with an outer endless ring of an inner resilient split-ring provided upon its inner surface with a toggle-joint 25 connecting the ends thereof, one portion of said toggle-joint being formed of spring wire and having a lateral loop extending beyond the edge of the split-ring.

3. An article of the character described, 30 comprising a split-ring and a toggle-joint

connecting the ends thereof, one of the members of said toggle-joint being formed of wire and provided with two lateral spring-loops to render the same resilient and one of said loops forming an operating means 35 for the toggle-joint.

4. An article of the character described comprising a split-ring and toggle-joint connecting the ends thereof, one of the members of said toggle-joint being formed of spring- 40 wire and provided upon the upper side with a downwardly extending loop and upon the under side with a corresponding downwardly extending loop.

5. An article of the character described, 45 comprising a split-ring provided adjacent each free end with a hinge-member secured upon the surface thereof, and a toggle-joint hinged to and extending between said hinge-members and comprising a flat non-resilient member, and a spring-wire member provided upon the upper side with a downwardly extending loop and upon the under side with a corresponding loop extending beyond the edge of the split-ring. 50

GEORGE BODEN.
